UNITED STATES PATENT OFFICE.

JOHN B. CORNELL, OF NEW YORK, N. Y.

FIREPROOF FLOOR.

Specification of Letters Patent No. 22,939, dated February 15, 1859.

To all whom it may concern:

Be it known that I, JOHN B. CORNELL, of the city, county, and State of New York, have invented a new and economical method 5 of forming a fireproof foundation upon a series of wooden girders for the reception of a flooring surface composed of boards or other suitable materials; and I do hereby declare that the following is a full and exact description thereof, reference being had to the accompanying drawings, making a part of this specification.

Figure 1, is a section of one of my improved fire-proof floors in the line x, x , of Fig. 2, and Fig. 2, is a section in the line y, y , of Fig. 1. Fig. 3, is a modification of Fig. 1.

In constructing my improved fire-proof foundation for a floor upon a series of 20 wooden girders, (a, a), I first secure to the upper edges of said girders a continuous covering of plaster-supporting metallic sheets (d, d). The said metallic sheets may either rest directly upon the upper edges of 25 the girders (a, a), or thimbles g, g , may be interposed between the two, as represented in the drawings. A series of wooden strips b, b , are then placed, at suitable intervals, upon the upper surface of the said plaster 30 supporting sheets, and are secured thereto either in the manner represented in the accompanying drawings or by any other suitable means. The next step in said invention is to thoroughly fill all the cavities in the 35 metallic sheets d, d , above and below, with moistened plaster of paris, (e), or some other nonconducting fire-proof composition, taking special and particular pains to force the said composition into all the spaces be-

tween upper surfaces of said girders and 40 the under surfaces of the metallic sheets. If deemed necessary, the fire-proof composition may be laid upon the upper sides of the metallic sheets (d, d) in sufficient quantity to raise its upper surface to a 45 level with the upper surfaces of the strips b, b , or a little above the same, as shown in the drawings.

Having thus constructed a perfectly fire-proof foundation for the flooring boards 50 c, c , I secure the said boards to the strips b, b , by either of the methods represented in the drawings, or by any other method that may be deemed expedient.

I employ screws instead of nails as the 55 means of securely retaining the flooring boards in their proper position, upon the fire-proof foundation, for the reason that they can be used without loosening the strips b, b , or producing any fractures in 60 the fire-proof composition which incloses said strips.

What I claim as my invention and desire to secure by Letters Patent, is—

Constructing a fire-proof foundation 65 upon a series of wooden girders for the reception of a flooring surface formed of boards, or other suitable materials, substantially as herein set forth.

The above specification of my new and 70 economical method of constructing fire-proof floors, signed and witnessed this 11th day of November, 1858.

JOHN B. CORNELL.
